UNITED STATES PATENT OFFICE

ELMER R. POPE, OF SOUTH HAMILTON, MASSACHUSETTS, ASSIGNOR TO UNITED SHOE MACHINERY CORPORATION, OF PATERSON, NEW JERSEY, A CORPORATION OF NEW JERSEY

FASTENING-SUPPLYING MECHANISM

Original application filed October 25, 1924, Serial No. 745,893. Divided and this application filed May 31, 1928. Serial No. 282,033.

This invention relates to fastening supplying mechanisms and is illustrated herein as embodied in means for supplying nails to a hand-operated nail inserting device.

5 It is an object of the present invention to provide improved means for supplying fastenings to a fastening inserting device and improved means for positioning and supporting a fastening inserting device for the reception 10 of fastenings from the fastening supplying means. My improved device is illustrated herein as supplying nails to a nail inserting implement of the character disclosed and claimed in Letters Patent of the United

15 States, No. 1,717,402, granted June 18, 1929, on my co-pending application Serial No. 745,893, filed October 25, 1924, of which this is a division, although the invention is not limited to use in such an implement.

20 Features of the invention comprise a novel arrangement by which the presence of a fastening inserting device in operative relation to the outlet of a source of fastening supply is operative to release a number of fastenings 25 which then pass from the source of supply to one or more guideways carried by the inserting device, and a novel supporting and positioning means for a fastening inserting device, illustrated as a spring clip together 30 with a plurality of gage members arranged to contact with the surface of the fastening inserting device, each over a small area, to support and position the fastening inserting device for the reception of fastenings from the

35 source of supply.

With the above and other features and objects in view, the invention will now be described in connection with the accompanying drawings and pointed out in the claims.

40 In the drawings,

Figs. 1 and 2 are a side elevation and a front elevation, respectively, each with certain parts in section, illustrating fastening supplying means embodying my invention as 45 delivering fastenings to a fastening inserting implement of the kind disclosed and claimed in said Letters Patent No. 1,717,402.

The illustrated mechanism for supplying fastenings to a fastening inserting device is 50 arranged to handle nails which it receives

from a hopper 60 provided with suitable mechanism, which may be of any usual type, to feed nails to a raceway or raceways 62. As illustrated, there is a pair of these raceways, the lower end of each being arranged 55 in alignment with a guideway consisting of a tube 64. Each tube 64 is long enough to contain sufficient nails to charge one of the nail receiving tubes of an inserting device, indicated in broken lines, which may be of the kind illustrated in said Letters Patent No. 1,717,402. The passage of nails from the raceways 62 to the tubes 64 of the supply device and from the tubes 64 to the nail receiving tubes of the nail inserting device is controlled by the presence of the nail inserting device with its nail receiving tubes in alignment with the tubes 64 of the supply device. In order that the nail inserting device may be 60 properly held in position, a spring clip 66, with its front open, is arranged readily to receive and to permit the removal of the nail inserting device. Three gage members 68 are provided with their surfaces so located that when the nail inserting device is inserted in the clip 66 and is pushed rearwardly against these gage surfaces, it will be properly positioned relatively to the nail supply means. For this purpose it is only necessary that each 65 of the gage members engage the nail inserting 70 device over a small area.

When the nail inserting device is inserted in the clip 66 for the reception of fastenings, its upper end engages a pair of lugs 70 carried by a slide 72 mounted in a bracket 74 of the supply device. A spring 76 housed in the bracket 74 tends normally to push the slide 72 outwardly so that portions of the slide are positioned beneath the outlet of the tubes 64 and prevent the passage of nails from these 75 tubes. On the other hand, when the slide 72 is pressed inwardly against the spring 76 by the insertion of the nail inserting device, the slide 72 passes out from under the outlets of the tubes 64 and the nails in those tubes are 80 free to drop into the tubes of the inserting device.

A pair of pivotally mounted stops 80 (the upper end of the left-hand one of which is 85 broken away in Fig. 2) are arranged for 90

movement into the path of feed of the end-most nail in each raceway 62. The stops 80 are fast upon a rock shaft 82 normally held by a spring 84 in the position shown in Fig. 1, in which the stops are just out of engagement with the fastenings in the raceways 62. An arm 86, also rigid with the rock shaft 82, engages the upper end of a rod 88 mounted for sliding movement with its lower end resting upon a cam surface 90 carried by the slide 72. Thus when the slide 72 is moved rearwardly, the rod 88 moves downwardly, the stops 80 rocking under the influence of the spring 84 into position to prevent the passage of nails from the raceways 62 into the tubes 64. At the same time, the nails in the tubes 64 drop into the tubes of the nail inserting device. When the nail inserting device is removed, the slide 72 is moved out by the spring 76 into position to prevent the passage of nails from the tubes 64, at the same time moving the rod 88 upwardly and rocking the stops 80 out of engagement with the nails in the raceways 62 so that the nails in the raceways may move downwardly filling the tubes 64.

While the invention is illustrated herein as embodied in a device adapted to handle nails of considerable size, for example nails such as are used for attaching rubber heels to shoes, it should be understood that its utility is not limited to the handling of fastenings of this character.

Having described my invention, what I claim as new and desire to secure by Letters Patent of the United States is:

1. A fastening supplying device arranged to feed fastenings to fastening inserting means, said device comprising a raceway, a guideway communicating with the outlet of the raceway and receiving fastenings therefrom, means movable to permit and prevent the passage of fastenings from the guideway, means arranged to control the passage of fastenings from the raceway to the guideway, and connections between said two means operative to cause the first to prevent the passage of fastenings from the raceway to the guideway when the second is moved into position to permit the passage of fastenings from the guideway.

2. A fastening supplying device arranged to feed fastenings to fastening inserting mechanism, said device comprising a raceway, a guideway communicating with the outlet of the raceway and receiving fastenings therefrom, a stop movable to permit or prevent the passage of fastenings from the raceway to the guideway, a slide arranged to control the passage of fastenings from the guideway, and connections from the slide to the stop operative to cause the stop to prevent the passage of fastenings from the raceway to the guideway when the slide is moved into

position to permit the passage of fastenings from the guideway.

3. A fastening supplying device arranged to feed fastenings to fastening inserting mechanism, said device comprising a plurality of raceways, a guideway communicating with the outlet of each raceway and receiving fastenings therefrom, stops movable to permit or prevent the passage of fastenings from the raceways to their respective guideways, a slide arranged to control the passage of fastenings from the guideways, and connections from the slide to the stops operative to cause the stops to prevent the passage of fastenings from the raceways to the guideways when the slide is moved into position to permit the passage of fastenings from the guideways.

4. A device for supplying fastenings to a fastening inserting implement, said device comprising a raceway, a tube receiving fastenings from the raceway, a stop mounted for movement into engagement with a fastening in the raceway to prevent the passage of fastenings from the raceway to the tube, means for preventing the passage of fastenings from the tube arranged for movement by engagement with a fastening inserting implement to which fastenings are to be supplied, thereby permitting the passage of fastenings from the tube to said implement, and connections between said means and the stop arranged to move the stop into engagement with the end-most fastening in the raceway when the fastening inserting implement is moved into fastening receiving position.

5. A device for supplying fastenings to a fastening inserting implement, said device comprising a raceway, a tube receiving fastenings from the raceway, a stop pivotally mounted for movement into engagement with a fastening in the raceway to prevent the passage of fastenings from the raceway to the tube, means for preventing the passage of fastenings from the tube arranged for movement by engagement with a fastening inserting implement to which fastenings are to be supplied, thereby permitting the passage of fastenings from the tube to said implement, and connections from said means to the stop arranged to swing the stop into engagement with a fastening in the raceway when the fastening inserting implement is moved into fastening receiving position and to remove the stop from engagement with the fastenings in the raceway when said means becomes operative to prevent the passage of fastenings from the tube.

6. A device for supplying fastenings to a fastening inserting implement, said device comprising means for positioning a series of fastenings in substantially axial alignment with each other, means for retaining the fastenings, means for positioning a fastening inserting implement relatively to the first men-

tioned means including a plurality of gage members positioned to contact with the fastening inserting implement, and means operated by the placing of the fastening inserting implement in fastening receiving position to render said retaining means inoperative.

7. A fastening supplying device arranged to feed fastenings to a fastening inserting implement comprising a raceway, a guideway communicating with the outlet of the raceway and receiving fastenings therefrom, means for controlling the passage of fastenings from the raceway to the guideway, retaining means for preventing the passage of fastenings from the guideway, means for positioning a fastening inserting implement for the reception of fastenings from the guideway including means for supporting the implement and a plurality of gage members arranged to position the implement relatively to the guideway, and means operated by the placing of the fastening inserting implement in fastening receiving position arranged to operate the fastening retaining means to permit the passage of fastenings from the guideway to the implement.

8. Means for positioning a fastening inserting implement relatively to mechanism for supplying fastenings thereto comprising a clip arranged to receive and support the fastening inserting implement, and a plurality of gage members positioned to contact with the fastening inserting implement when the latter is held by the clip with its fastening receiving parts in alignment with the fastening discharging parts of the fastening supplying mechanism.

9. Means for positioning a fastening inserting implement relatively to mechanism for supplying fastenings thereto comprising a spring clip arranged to receive and support the fastening inserting implement, and three gage members positioned to contact with the fastening inserting implement when the latter is held by the clip with its fastening receiving parts in alignment with the fastening discharging parts of the fastening supplying mechanism.

10. Means for positioning a fastening inserting implement for the reception of fastenings comprising resilient means for supporting a fastening inserting implement constructed and arranged for the ready reception and release of said implement, and a plurality of gage members each arranged to contact with the surface of the fastening inserting implement over a small area to position said implement in the supporting means.

11. Means for supplying fastenings to a fastening inserting implement having spring means for supporting a fastening inserting implement constructed and arranged for the ready reception and release of said implement, and three gage members each arranged to contact with the surface of the fastening insert-

ing implement over a small area to position said implement in the supporting means for the reception of fastenings.

In testimony whereof I have signed my name to this specification.
